HARRY J. LINGAL, OF PITTSBURGH, PENNSYLVANIA, ASSIGNOR TO WESTINGHOUSE ELECTRIC & MANUFACTURING COMPANY, A CORPORATION OF PENNSYLVANIA

TOGGLE LATCH

Application filed May 12, 1927. Serial No. 190,712.

My invention comprises a trigger latching mechanism and more particularly a locking member therefor.

One object of my invention is to provide a trigger and a latch with a mechanism that securely locks it into closed position.

Another object of my invention is to provide a trigger with a spring-biased toggle that is released by the latch before coming into engagement with the trigger.

A further object of my invention is to provide a trigger and a latch with a locking toggle that is biased to its center or beyond its center position by a spring member and is released therefrom by the operation of the tripping mechanism.

Heretofore, circuit breakers and other apparatus requiring trigger mechanism for supporting a latch to retain a member in a specific position might become unlatched prematurely by vibration or shock transferred to the trigger member. In order to prevent premature opening and to ensure a positive locking condition, I have devised my toggle mechanism which can be better understood by referring to the drawings, in which,

Figure 1 is a view, partly in elevation and partly in section, showing an embodiment of my invention in its closed and locked position.

Fig. 2 is a similar view showing the tripping mechanism energized for releasing the toggle and the trigger.

My invention comprises, in general, a circuit interrupter 1 or other similar device requiring a trigger 2 and a latch 3 that requires a positive locking member to retain the trigger and latch in engagement until positively tripped by the tripping mechanism.

The trigger 2 is hingedly supported on a member 4 by a pin 5 and comprises also a pin 6 at its opposite end. A projection 7 engages a roller 8 of the latch 3 and thereby prevents the latch from moving in an upward direction. The pin 6 pivotally supports one member 9 of the toggle mechanism; the other member 11 being pivotally supported by a pin 13. The adjacent ends of the members 11 and 9 of the toggle mechanism are connected by a pin 14.

The toggle member 11 has arms 15 and 16

and a stop member 17 adjacent to each other near the pin 13. The arm 15 is provided with a hole 18 through which a rod 19 freely projects. The rod 19 acts as a guide for a spring 21 and a guide washer 22 for biasing the toggle mechanism 11 toward its forward position, thus holding the pins 14, 6 and 11 in substantially the same plane or slightly beyond the dead-center position of the toggle mechanism. The spring 21 acts upon the arm 15, the toggle members 11 and 9 and the pin 6 to bias the trigger 2 to a forward position in which its projection 7 engages the roller 8 of the latch 3. The arm 16 of the toggle member 11 is so placed that, when struck by the stem 23 of the core of the solenoid 24, the toggle member 11 is moved in a clockwise direction to overcome the biasing force of the spring 21 and move the trigger projection 7 out of engagement with the roller 8.

The toggle member 9 comprises also an extension 25 that projects beyond the projection 7 to be engaged by the roller 8 for upsetting the toggle mechanism when the latch 3 is moved downward to effect latching engagement of its roller 8 with the projection 7. The stop 17 on the toggle member 11 operates to prevent the spring 21 from moving the toggle mechanism too far forward by striking against a shoulder 26 of the supporting member 12.

Assuming the circuit interrupter to be in the open position, the latch 3 will be in a raised position similar to that shown in Fig. 2, and the toggle mechanism and the trigger will be biased to their forward positions, as shown in Fig. 1.

Upon downward movement of the latch 3, the roller 8 strikes against the extension 25 of the toggle member 9 and thus moves the member in a counter-clockwise direction, thereby moving the pin 14 above the plane through the centers of the two pins 6 and 13. The trigger 2 is thus released to permit the roller 8 to pass the projection 7 of the trigger.

The spring 21 thereupon biases the toggle member 11 in a counter-clockwise direction to move the trigger 2 into the position shown in Fig. 1. The continued biasing action of

the spring 21 moves the pin 14 downwardly to or beyond the plane of the pins 6 and 13, thereby locking the trigger 2 in the position shown in Fig. 1.

5 To release the latch 3, the solenoid 24 is energized, thereby moving the stem 23 upward into engagement with the arm 16, which imparts a clockwise movement to the toggle member 11. The pin 14 is thereby moved from the center position to effect a clockwise movement of the trigger 2. This move the projection 7 out of engagement with the roller 8 of the latch 3, which is thereby released.

15 Upon deenergization of the solenoid 24, the stem 23 drops downward to release the arm 16, and the toggle member 11 is moved in a counter-clockwise direction by the spring 21 until the stop member 17 engages the stop 26 of the support 12. The trigger 2 is again 20 locked in its latching position from which it can be moved only by a force acting on the projection 25 of the member 9.

25 Accordingly, I have invented a simple locking mechanism for a trigger that is positive in its operation and that functions to prevent the opening of the interrupter from shock or vibration that may be imparted to it.

It is to be understood that changes in the form, arrangement and connections of the 30 component parts of my invention may be made without departing from its principle. I desire, therefore, that the scope thereof shall be limited only as indicated in the appended claims.

35 1. I claim as my invention:

1. The combination with a latch arm, of a trigger adapted to restrain it, a fixed fulcrum for supporting the trigger, a toggle mechanism for locking the trigger in engaging position and a spring for actuating the toggle mechanism to locked position.

40 2. The combination with a trigger, of a latch engaged thereby, a toggle for locking the trigger in latch-engaging position, means adapted to be engaged by the latch to upset the toggle to permit the latch to be engaged by the trigger, and a tripping mechanism adapted to operate the toggle and the trigger to release the latch.

45 3. The combination with a trigger, of a locking mechanism therefor, a latch engageable by the trigger to retain it in fixed position, releasing means on the locking mechanism operated by the latch when moved into engagement with the trigger and a tripping mechanism for operating the trigger to release the latch.

50 4. The combination with a latch arm, of engaging means for retaining the arm in fixed position, a toggle mechanism comprising two members pivoted together for locking the engaging means.

55 5. In combination, a trigger, a latch, a spring-biased toggle mechanism for locking the trigger in fixed position, one of its mem-

bers having a projection to be engaged by the latch during its movement into engagement with the trigger, and an additional means for upsetting the toggle mechanism and the trigger after the latch has been engaged thereby.

6. The combination with a latch arm, of engaging means for retaining the arm in fixed position, a toggle mechanism comprising two members pivoted together for locking the engaging means and projections on each of the members adapted to be engaged for upsetting the toggle mechanism.

7. The combination with a latch arm, of a trigger for retaining it in fixed position, a toggle mechanism comprising two members pivoted together for locking the trigger in fixed position, each of the members having a projection to be engaged to upset the toggle mechanism, and a biasing member for retaining the toggle mechanism in locked position.

8. The combination with a latching arm, of a trigger for engaging said latching arm, a toggle mechanism hingedly supported at one end and having its other end pivotally attached to the end of the trigger, a spring for forcing the trigger into engaged position and to secure it therein by forcing the toggle mechanism to or beyond its dead center, and upsetting means for the toggle mechanism operated by the latch before its engagement with the trigger.

9. The combination with a latch, of a trigger for engaging the latch, a fixed fulcrum for supporting the trigger, a toggle mechanism for locking the trigger in position and means for biasing the trigger and the toggle mechanism to locking position.

10. In combination, a trigger, a latch, a toggle mechanism for locking the trigger in engaging position, one member of the toggle mechanism having a projection to be engaged by the latch to operate the toggle mechanism and to permit the latch to move into latching engagement with the trigger.

In testimony whereof, I have hereunto subscribed my name this 5th day of May, 1927.

HARRY J. LINGAL.
